AUTOMATIC SEWER FLOOD CONTROL

Filed June 9, 1945

FIG. 1.

FIG. 2.

Inventor:
Arthur Gordon,
By Clinton Miles Schaefer,
Merriam, Foggan, Atty's.

UNITED STATES PATENT OFFICE

2,431,640

AUTOMATIC SEWER FLOOD CONTROL

Arthur Gordon, Chicago, Ill.

Application June 9, 1945, Serial No. 598,433

6 Claims. (Cl. 182—26)

1

The present invention relates to an automatic backwater locking gate and particularly to a gate adapted for control of a flooded sewer.

One object of this invention is to provide a gate which will automatically shut to prevent backflow of sewage into a building. Another object is to provide a gate that will automatically open when the backflow of sewage has ceased. An advantage of the invention is its extreme simplicity but positive action and the use of but very few moving parts.

The invention is not limited to sewage flood control but is applicable to any location where it is necessary to control backflow, or flood, or where any other control of liquid is required. Furthermore, the invention is not limited to new constructions but may be installed at small cost in connection with most of the present sewage pumps, sumps or ejectors.

Other objects and advantages will be apparent from the following which, taken in connection with the accompanying drawings, discloses a preferred embodiment of the invention.

Referring to the drawings: Figure 1 is a side plan view partly in cross-section of a sewage disposal system equipped with the novel invention; and Figure 2 is a vertical cross-sectional view taken on the line 2—2 of Figure 1.

In the embodiment of this invention shown in the drawings, 10 represents a sewer pipe into which waste water, sewage and the like from a building 11 is conducted by gravity to a street sewer 12. The sewer pipe passes through a basin or sump 13 below the floor 14 of the building. The upper part of the sewer pipe is cut away in this basin or sump to provide a spillway 15 and at the end of the other section near the street the pipe is completely broken away at 10a a sufficient amount to receive the novel gate 16 of suitable non-rusting material and adapted to close the pipe when lowered to the bottom thereof, the gate being formed with a semi-circular beveled lower end 17.

The gate is slidable in a guideway 18 of suitable material such as a non-rusting metal and having ears or flanges 19 extending therefrom and connected by bolts 20 to the side wall 21 of the sump to which they are secured by nuts 22. The sides of the guide are preferably spaced apart a little greater than the thickness of the gate so that the gate may freely slide therebetween.

The gate 16 is on the end of a rod 23 the upper end of which is provided with a gear rack 24 in a grease-filled box 25 above the building

2

floor 14. This rack meshes with one side of a circular gear 25a suitably fixed to shaft 26 journaled in opposite sides of the box 25. On the side of the gear 25a opposite the gear rack 24 the gear is engaged by a rack 27 on the end of a rod 28 on the bottom of which is a ball float 29.

The top of the rod 28 is provided with an enlarged portion 30 adapted to contact an arm 31 of switch 32 which operates motor 33 connected by a rod in pipe 34 to sump or bilge pump 35. This pump is connected with a discharge line 36 which extends upwardly through the top 37 of the basin or sump 13 to a point well above the building floor 14. It is there attached to a horizontal pipe 38 which extends to a point near the building wall where it is connected to a pipe 39 leading to the sewer pipe 10. The horizontal pipe 38 is provided with a check valve 40 to prevent backflow to the pump and with a removable plug 41 to permit cleaning out of the pipe and valve.

The basin or sump 13 may be square or circular as desired and is preferably made with integral bottom 42 and sides 21 but with the top 37 removable to permit cleaning of the basin or sump and repair of the motor or gate. The bottom of the basin is located well below the pipe 10 so as to eliminate operation of the gate except in flood conditions.

In operation the device functions as follows: Sewage, waste water and the like normally flows through the pipe 10 to the street sewer by gravity, the level of liquid in the pipe 10 being below the cutout portion or spillway 15 of the pipe. Should an unusual amount of liquid flow through the pipe some of it will spill over into the basin or sump 13 where it will remain, or from which it will be removed by the pump 35 operated intermittently or manually as the case may be and in a well known manner, but this operation not being a part of this invention will not be described further. During this normal operation the ball 29 being heavier than the gate 16 will remain at rest slightly above the upper edge of the spillway 15 and will keep the gate open.

When a flood or other abnormal condition causing backflow of the liquid from the street sewer to the building sewer occurs the liquid will overflow into the basin 13 until it causes the ball to rise to the position shown in the drawings. As the ball rises it lowers the gate until it completely closes the opening 10a in the sewer pipe and prevents further backflow into the basin. As soon as the ball rises the projection 30 on top of the rod 28 releases the arm 31 of the

switch 32 and the motor operates to pump out the liquid in the basin 13 through the pipes 36, 37 and 38 to the sewer pipe 10. Should the pump lower the liquid below the level necessary to maintain the ball float in position to shut the gate, the float will remain suspended in such position as the back pressure against the gate will more than offset the heavier weight of the ball.

As the flood subsides, however, this back pressure will cease and permit the float to descend and open the gate 16. Normal gravity flow in the pipe 10 will then be resumed.

If desired, the motor, pump and bypass pipes 36, 38 and 39 may not be used as the gate will operate successfully without them. In such case the upper edge of the spillway will preferably be flush with the floor or bottom 42 of the basin, so that when the flood subsides all the overflow will drain out the pipe 10. In such case, however, the normal sewage, etc., from the building will remain in the basin during the flood period. This is not a desirable condition and the use of the motor, pumps, etc. with the gate is greatly preferred.

While I have shown and described certain embodiments of my invention it is to be understood that it is capable of many modifications. Changes, therefore, in the construction and arrangement may be made without departing from the spirit and scope of the invention as disclosed in the appended claims in which the term flood condition means any abnormal condition causing back flow in the building sewer pipe or other conduit.

What I claim as new, and desire to secure by Letters Patent is:

1. An automatic back-water locking gate comprising: a sump basin; a conduit extending through said basin and having an opening therethrough and a spillway, both being located in said basin; a guide member adjacent said opening; a gate member slidable in said guide and adapted to close said conduit; a control member geared to said gate member and adapted to maintain said gate in open position during normal conditions and to close the gate automatically under flood conditions whereby backwater is prevented from reaching the basin, said members being so constructed and arranged that the back pressure resulting from said flood condition will maintain said gate in closed position while said condition exists.

2. An automatic back-water locking gate comprising: a sump basin; a conduit extending through said basin and having an opening there-

through and a spillway, both being located in said basin; a guide member adjacent said opening; a gate member slidable in said guide and adapted to close said conduit, said member having a gear rack on its upper end; a gear meshing with said rack; and a ball float member having a gear rack meshing with said gear and adapted to maintain said gate member in open position during normal conditions and to close said gate automatically under flood conditions, whereby backwater is prevented from reaching the basin.

10 3. In a sewage disposal system having a sewage pipe extending through a sump basin to a street sewer; a spillway in said pipe in said basin; a guideway adjacent the street sewer end of said spillway; a gate in said guideway adapted to close said pipe, whereby sewage from said street sewer is prevented from entering the basin; a ball float geared to said gate to maintain it in

15 open position during normal conditions and to close it automatically under flood conditions; and automatic means for pumping the contents of said basin to the street sewer when said gate is closed.

20 4. In a liquid conduit a sump basin; a pipe extending therethrough and having a spillway therein; a guideway adjacent the normal discharge end of the spillway; a gate in said guideway adapted to open and close said pipe; a rod on said gate extending through the top of the basin; a gear meshing with said rack; a ball float in said basin and connected to a rod having a gear rack meshing with said gear; a pump in said 25 basin; a motor actuated by said ball float rod for operating said pump; and a by-pass conduit from said pump to a portion of said pipe on the exterior of said basin.

30 5. The device of claim 1, in which the spillway is an open section of the pipe above the normal level of flow of the liquid in the pipe.

35 6. The device of claim 1, in which the control member is a ball float.

ARTHUR GORDON.
